UNITED STATES PATENT OFFICE.

HENRY CLAY FOWLER, OF BURLINGTON, NORTH CAROLINA, ASSIGNOR OF ONE-HALF TO EDWIN C. HOLT, OF WILMINGTON, NORTH CAROLINA.

BOBBIN-LATCH.

SPECIFICATION forming part of Letters Patent No. 634,662, dated October 10, 1899.

Application filed June 22, 1899. Serial No. 721,480. (No model.)

To all whom it may concern:

Be it known that I, HENRY CLAY FOWLER, a citizen of the United States, residing at Burlington, in the county of Alamance and State 5 of North Carolina, have invented a new and useful Bobbin-Latch, of which the following is a specification.

This invention relates to bobbin-latches for shuttles; and it has for its object to provide 10 a construction in which a pivoted spindle is adapted to receive a bobbin and in which when said spindle is moved to lie in its operative position in the shuttle the bobbin will be held against accidental displacement from the 15 spindle.

In the drawings forming a portion of this specification, and in which like numerals of reference designate corresponding parts in the several views, Figure 1 is a side elevation 20 of a shuttle partially broken away to show the location and arrangement of the bobbin and its latch. Fig. 2 is a side elevation of one end of the shuttle, partially in section, and also showing the bobbin and adjacent portions, 25 some in elevation and some in section. Fig. 3 is a section on line 3-3 of Fig. 2 with the bobbin removed and showing the position of the elements of the latch when the latter is closed and the bobbin is ready to be rocked 30 into the shuttle, the central block being shown in elevation. Fig. 4 is a view similar to Fig. 3, showing the latch in its disengaged position. Fig. 5 is a rear elevation of the latch-plate.

Referring now to the drawings, 5 represents a shuttle of common form having a longitudinal slot therein, in which is pivoted a tongue 6 through the medium of a pin 7 passed through the enlarged head 8 of the tongue. 10 This head at the adjacent extremity of the tongue has flattened faces adapted for engagement of a retaining-spring 9, which latter when engaging corresponding faces of the head hold the tongue in either an extended 15 position or within the inclosure of the shuttle in the usual manner.

It is of course understood that the tongue is pivoted at one end of the slot of the shuttle in the usual manner.

50 The head 8 of the tongue has a greater di-

ameter than the tongue and is angular in cross-section, and the tongue is set inwardly from the edge of the head, resulting in the formation of a shoulder 10, extending completely around the tongue, and resting upon 55 this shoulder is an eccentrically-mounted cylindrical block 11, adapted to receive a bobbin 12 of the usual construction, the lower end of which bobbin rests upon the upper radially-serrated face of an annular flange 13 60 adjacent the lower end of the block 11, the bobbin when in this position being disposed at a slight angle to the tongue 6, as will be readily appreciated.

In order to hold the bobbin upon the tongue 65 and to allow the removal thereof, the eccentric block 11, which is rotatable upon the tongue, is adapted in its rotation to move the base of the bobbin toward or away from a latch-plate 15, riveted, as shown at 21, or otherwise secured to the head 8 and extending upwardly therefrom and parallel with the block 11, said upwardly-extending portion having at its upper edge an inwardly-directed flange 16, which is arc-shaped to conform to the contour of the bobbin and to enter an annular groove 17 therein. The extension of the latch-plate 15 is arc-shaped in cross-section, as shown 70 in Fig. 5. The arrangement and proportions of these elements are such that when the bobbin is rotated with the block 11 its groove 17 will be moved into or out of engagement with the flange 16, a tangential lug 18 upon the flange 13 being positioned to engage the adjacent edge of the extension of the plate 15 to act 75 as a stop for the rotation of the block 11 when the block is in a position to engage the flange 16 with the groove 17, the length of said lug being such that when the tongue lies in the slot of the shuttle the wall of the slot will limit outward movement of said lug and consequent rotation of the block 11 and the parts carried thereby. Thus when the tongue is in the position shown in Fig. 2 of the drawings the bobbin may be readily applied to or removed 80 therefrom; but after the tongue is rotated to the position shown in Fig. 3 and the parts are then moved upon the pivot 7 to lie within the slot of the shuttle, as shown in Fig. 1, it will be impossible to rotate the block 11 suf- 85 90 95 100

fiiciently far to disengage the groove 17 of the bobbin from the flange 16.

As shown in Fig. 2 of the drawings, a collar 20 upon the tongue 6 prevents displacement 5 of the block 11 longitudinally of the tongue, and it will of course be understood that in practice various modifications may be employed and that the specific construction and arrangement may be varied without departing 10 from the spirit of the invention.

Having thus described the invention, what is claimed is—

1. The combination with a shuttle and the tongue thereof, of a latch-plate connected 15 with the tongue, and a block pivoted upon the tongue and adapted to receive a bobbin and rotate it into engagement with the latch-plate.
2. The combination with a shuttle and the 20 tongue thereof, of a latch-plate connected with the tongue, and a block eccentrically pivoted upon the tongue and adapted to receive a bobbin and move it into engagement with the latch-plate.
- 25 3. The combination with a shuttle and a tongue thereof, of a latch-plate connected with the tongue and having a projection, and a block pivoted eccentrically of the tongue and adapted to receive a bobbin and move it 30 into engagement with the projection of the latch-plate.
4. The combination with a shuttle and a tongue thereof, of a latch-plate connected with the tongue, and a block eccentrically 35 pivoted upon the tongue and having a serrated flange, said block being adapted to receive a bobbin in engagement with said serrated flange.

rations and move it into engagement with the latch-plate.

5. The combination with a slotted shuttle 40 and a tongue mounted in the slot thereof and adapted to receive a bobbin of a latch connected with the tongue adapted to engage and hold the bobbin upon the tongue, and means engaging the wall of said slot for preventing 45 disengagement of the latch when the bobbin is in the slot.

6. The combination with a shuttle having a slot therein, of a tongue pivoted within the slot, a latch-plate connected with the tongue, a block mounted upon the tongue and adapted to receive a bobbin and move it into engagement with the latch-plate, and means movable into and out of said slot to engage a wall thereof when in the slot and prevent rotation of the block.

7. The combination with a shuttle having a slot therein and a tongue pivoted in the slot, of a block eccentrically mounted upon the tongue and adapted to receive a bobbin 60 and move it, a latch-plate adapted to engage the bobbin when moved by said block, and a projection upon the block movable into and out of the slot of the bobbin to engage a wall thereof when in the slot and prevent movement of the bobbin from the latch-plate.

In testimony that I claim the foregoing as my own I have hereto affixed my signature in the presence of two witnesses.

HENRY CLAY FOWLER.
